DESIGN FOR A DRESS

Samuel Reich, Chicago, Ill.

Application January 27, 1941, Serial No. 93,420

Term of patent 3½ years

To all whom it may concern:

Be it known that I, Samuel Reich, a citizen of the United States of America, residing in Chicago, county of Cook, and State of Illinois, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

I claim:

The ornamental design for a dress, as shown.

SAMUEL REICH,
